US00D909332S

(12) **United States Design Patent** (10) **Patent No.:** **US D909,332 S**
(45) **Date of Patent:** ** *Feb. 2, 2021

(54) **LOUDSPEAKER**

(71) Applicant: **Harman International Industries, Incorporated**, Northridge, CA (US)

(72) Inventor: **Nikola Sretovic**, Shenzhen (CN)

(73) Assignee: **Harman International Industries, Incorporated**, Northridge, CA (US)

(*) Notice: This patent is subject to a terminal disclaimer.

(**) Term: **15 Years**

(21) Appl. No.: **29/683,654**

(22) Filed: **Mar. 14, 2019**

(51) LOC (13) Cl. **14-01**

(52) U.S. Cl.

USPC **D14/204**; D14/216

(58) **Field of Classification Search**

USPC D14/204, 205, 221, 223, 210–216

CPC H04R 1/025; H04R 1/026; H04R 1/26; H04R 1/2888; H04R 1/403

See application file for complete search history.

(57) **CLAIM**

The ornamental design for a loudspeaker, as shown and described.

DESCRIPTION

FIG. 1 is a top perspective view of a loudspeaker showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof; and,

FIG. 7 is a bottom view thereof.

The broken lines and unshaded areas in the figures illustrate portions of the design that form no part of the claimed design.

1 Claim, 7 Drawing Sheets
